Primary Examiner — Darlington Ly*Assistant Examiner* — Katherine A Holbrow(74) *Attorney, Agent, or Firm* — Leason Ellis LLP(57) **CLAIM**

The ornamental design for a display screen with transitional graphical user interface, as shown and described.

DESCRIPTION

FIG. 1 is a front view of a first embodiment of a display screen with transitional graphical user interface according to the claimed design; and

FIG. 2 is a second image thereof.

The appearance of the transition is sequential from FIG. 1 to FIG. 2. The process or period in which an image transitions to another image forms no part of the claimed design.

The shading shown in the figures portrays a contrast to other features in the claimed design.

The outermost broken line rounded rectangle showing an electronic device illustrates environmental subject matter. The broken line showing a display screen and all other broken-lines showing portions of the graphical user interface illustrate portions of the article. None of the aforementioned broken line subject matter forms part of the claimed design.
